to Dermetics, Inc., New York, N. Y., a corporation of Washington

Application February 24, 1949, Serial No. 1,044

Term of patent 14 years

(CL. D58—6)

To all whom it may concern:

Be it known that I, Josephine von Miklos, a citizen of the United States, residing at New York city, in the county and State of New York, have invented a new, original, and ornamental Design for Bottles, of which the following is a specification, reference being had to the accompanying drawing, forming part thereof.

Fig. 1 is a top plan, and

Fig. 2 is a side elevational view of a bottle, showing my new design.

I claim:

The ornamental design for a bottle, as shown.
JOSEPHINE von MIKLOS.
